UNITED STATES PATENT OFFICE.

HENRY E. RATHBUN, OF WORCESTER, MASSACHUSETTS.

LOOM FOR WEAVING SHORT-WEFT FABRIC.

971,072.

Specification of Letters Patent. Patented Sept. 27, 1910.

Application filed March 15, 1909. Serial No. 483,377.

To all whom it may concern:

Be it known that I, HENRY E. RATHBUN, a citizen of the United States, residing at Worcester, in the county of Worcester and 5 State of Massachusetts, have invented a new and useful Loom for Weaving Short-Weft Fabric, of which the following is a specification.

This invention relates to a loom for weaving short weft fabrics although some parts 10 of it are capable of general use.

The principal objects of the invention are to greatly reduce or entirely eliminate the stoppages due to the failure of the weft 15 feeding means to introduce a weft into the fabric. Under the present conditions these stoppages are frequent and the time required for the operator to put things right after a weft strand has been fed in from the 20 wrong side is as much as would be consumed in making a large number of picks if the loom had not stopped. This greatly reduces production and increases the cost of fabrics of this kind. Heretofore so far as I am 25 aware, the attempts which have been made to overcome this difficulty have always been in the line of providing more efficient means for stopping the loom when a pick is missed, or a more efficient picker, which is almost 30 impossible on account of the variation in the size of straw.

This invention is designed to overcome the difficulty in an entirely different way, 35 namely by providing automatic means whereby when a pick is missed from one side of the loom the next pick from the other side will also be missed without stopping the loom, and also if this miss-pick is caused by a short weft the latter will automatically 40 be drawn out of the way so that on the next pick it will not prevent the next weft from being fed forward, so that the loom can continue to operate provided the next pick from the side which first missed is brought 45 in in the regular way. In this way no time is lost and the only disadvantage is the mere loss of two picks in the cloth which of course is negligible, because the next pick from the side first missed comes in in the proper place 50 and the weaving goes on as usual.

Other objects for accomplishing this result so constructed that it works every time no matter which side of the loom the miss-pick is on, and no matter how many times 55 or in what order the missing of the picks is

repeated, and to provide means whereby the take-up is caused to cease operating as long as the loom continues to miss picks.

Further objects and advantages of the invention will appear hereinafter.

Reference is to be had to the accompanying drawings in which—

Figure 1 is a plan of a portion of a short weft loom showing a preferred embodiment of the invention applied thereto; Fig. 2 is 60 a side view of the same showing the position of the parts when the weft is inserted and everything is going on in the normal way; Fig. 3 is a similar view showing the position of the parts when a pick is 65 missed; Fig. 4 is an end view of a portion of the parts under the same conditions when the lay has beaten clear back and showing the side of the loom from which the pick is missed; Fig. 5 is a similar view of the other 70 side of the loom at the same time; Figs. 6, 7, 8 and 9 are views of a somewhat diagrammatic form showing several positions of the parts during the operation after a pick is 75 missed; Fig. 10 is a plan of part of the 80 take-up motion; Fig. 11 is side view of the same; Fig. 12 is a diagrammatic view showing how a weft is fed into the loom and why a short weft is not discharged from the weft hopper into the shed; and Figs. 13, 14 and 85 15 are end views of the same showing how a short weft which has been missed is taken out of the hopper automatically so as to prevent the stoppage of the loom and allow 90 the next weft to be fed in in the usual 95 manner.

This invention is shown as applied to a type of short weft fabric loom having a lathe 18 and a breast-beam 19 and in which there are feeding rolls or brushes 20 and 21 100 on the lathe, the roll 20 being mounted to turn on a stationary axis and the roll 21 oscillating back and forth toward the roll 20 so that the roll will come into contact to feed a weft in as shown at the left of Fig. 1, alternately from the two sides. The roll 21 is operated by a feed roll carrier shown as a lever 22, rod 23, and cam 24 and rotated by spiral gears 25 or in any other desired 105 manner, as is well understood at the present time in this art.

In accordance with this invention the feed roll carrier is preferably provided with a projection 26 and on each end of the lathe 110 is pivoted a lever 27 having a lug 28 adapt-

ed to engage this projection and hold the roll 21 out of contact with the roll 20 as shown in Fig. 5. Adjustable means in the form of a screw 29 is shown for limiting the 5 position of the lever and a spring 30 for operating it in one direction.

In order to provide a miss pick controlling device operated by the shed the following mechanism is shown for controlling the 10 operation of the lever 27. Journaled in brackets 31 on the lathe is a shaft 32 which extends across the lathe and has on each end thereof an arm 33 extending from the shaft, said arms carrying a bar 34 between them 15 which is adapted to extend up into contact with the warp threads of the shed. At one end the shaft also has an arm 35 extending in the opposite direction and provided with a spring 36 for normally holding the bar 34 20 up against the shed as shown in Fig. 2. It is the operation of this bar by the warp threads which controls the missing of the picks as will be explained hereinafter.

At the opposite ends of the shaft 32 are 25 arms 40 pivotally mounted on which are levers 41, the arms being provided with springs 42 to hold said levers normally in the position shown in Fig. 3 and to turn them to that position when released from 30 other holding means. Each of these levers is provided with a projection 44 having a spring 43 thereon normally engaging the top of the forward end of the lever 27 as is shown in Fig. 2. It will be seen therefore 35 that when a weft thread is introduced into the warp as shown in Fig. 2, the spring 36 is permitted to hold the bar 34 up under the warp and then the shaft 32 is thrown to such position that the levers 41 project 40 out substantially parallel with the levers 27 and the springs 43 hold the forward ends of these levers 27 down so that the projections 28 thereof cannot engage the lugs 26 on the rollers 21. The parts are then in the 45 position shown in Figs. 2 and 4, and as long as a weft is introduced alternately from each side in regular order the parts will always return to this position so that there will be no hindrance to the proper operation 50 of the loom. When a pick is missed, however, the warp threads will assume the position in which they are shown in Fig. 3. This bears the bar 34 down in opposition to the force of the spring 36 and brings the 55 arm 40 backward. This releases the levers 27 from the force of the springs 43 which are stronger than the springs 30, and allows the springs 30 to act. As the parts are shown the force of gravity would act in 60 this case to bring the rear ends of the levers 27 down into such position that they can engage the rear ends of the lugs 26.

With this particular description of the 65 operation of these parts the rest of the mechanism will be readily understood.

Mounted near the ends of the breast-beam are two brackets 45, each of which carries a stationary spear 46. Under this is located a fixed pin 47 parallel with the spear and on this pin is mounted a sleeve 48 having a 70 notch 49 in the bottom thereof and provided with a spring 50. This notch is for receiving a pin 51 in the forward end of the lever 27. One of the spears is provided with a 75 pin 52 and the bracket is provided with a projection 53 supporting a bell-crank 54, one end of which is adapted to engage the pin 52, and to the other end of which is secured a flexible connection 55 which is connected with a pivoted pawl 56 on the take-up motion 57, this pawl being adapted to engage a toothed wheel 58 and to move 80 down by gravity ordinarily so as to feed the wheel one or more notches for every pick of the loom. It will be understood that the 85 lever 59 on which the pawl 56 is mounted is operated by a link 60 in any usual way, and that the wheel 58 operates the take-up motion through the shaft 61 in any ordinary manner.

When the parts have operated in the manner shown in Figs. 2 and 4 as above described, the feed rolls, while on the backward movement, come together so as to feed the weft before the harnesses commence to 95 change and the parts are left in the position shown in Fig. 2, bringing the levers 27 on both sides down so that the pins thereon will pass under the sleeves 48 on both sides when the lay beats up. This movement is 100 repeated every time a strand of weft is taken into the shed or warp from either side.

Whenever a strand of weft is not deposited between the feed rolls so that it is not 105 fed into the shed, the operation is as follows:—The lay comes forward without the weft between the rolls on one side and on the next backward movement of the lay these feed rolls are brought together as 110 usual, but no weft being deposited between them none is carried into the shed, and when the harnesses change, the warp, as has been stated before, assumes the position shown in Fig. 3, carrying down the bar 34 and raising the lever 41 from the lever 27 so as to allow the end 28 to drop on the lug of the feed roll carrier on that side which is in its extreme backward position and the end of the other lever 27 to drop over the lug 26 of 115 the feed roll on that side which is in its extreme forward position. This brings one lever 27 into the position shown in Fig. 4 and the other into the position shown in Fig. 5. On the forward movement of the 120 lathe the pin 51 on the lever 27 on the side that missed passes under the sleeve 48 while the pin on the other lever passes between the sleeve on that side and the spear 46. On the next backward movement of the 125 130

lathe the pin 51 on the lever which passed under its sleeve engages the notch 49 of the sleeve as shown in Fig. 8, drawing the sleeve backward with the movement of the lathe. These positions will be maintained, preventing the side of the loom which did not miss originally from feeding a weft strand into the loom until a strand has passed into the shed of the warp from the side which has originally missed, so as to again bring the parts into the position shown in Fig. 2, thereby lowering the lever 41 and setting the levers 27 on both sides. The downward movement of the lever 27 caused by the lever 41 on the side which originally missed releases the pin 51 from engagement in the notch 49 thereby letting the sleeve return to its original position by the action of its spring 50. Then when the lathe comes forward again, the pins 51 will both pass under the sleeve, but however, if the strand of the weft is not taken between the feed rolls on either side in their proper turn, the warp will again assume the position shown in Fig. 3, depressing the levers 27 and allowing the projections 28 to drop either on or over their respective lugs 26 on the feed roll carriers according to the backward or forward position of such lugs.

The lever on the side from which a pick has missed always drops on the top of its lug and passes under the sleeve 48 so as to remain in that position, carrying the sleeve forward and backward by the movement of the lay until a strand of weft has been deposited between the sheds of the warp on that particular side. The lug 28 on the opposite side of the loom will drop over the feed roll lug 26 on that side so the pin 51 on that side will pass between the parts 46 and 48, causing it to be held over its feed roll lug so that when the feed rolls on this side move toward each other the movement is arrested by the lug coming in contact with the projection 28, thereby holding the feed rolls far enough apart to prevent their feeding a weft strand until one has come in from the opposite side. Of course when that happens the arm 33 will again operate the levers 41 and 27 so as to raise the projections 28 out of engagement with the lugs 26 on both sides. This permits the pins 51 to pass under their sleeves which is always the correct position when a strand of the weft has passed into the shed. It will be seen, therefore, that the projections 28 always drop on the lug 26 on the particular side from which a strand of the weft has been missed, causing the pin 51 to be locked with the sleeve 48 and holding the parts in that position until the strand of weft has been fed in from that side, while the opposite lug 28 drops over its particular feed roll lug 26 and thereby holds the feed rolls on that side, so that they will not feed in a strand until a strand has

been fed in from the other side, which, of course, can be done because the projection 28 on the other side does not prevent it. In case of a plurality of miss picks occurring in succession the parts continue to hold the above described positions until a strand is fed in from the side which originally missed, so that always an even number of picks will be missed.

It will be readily seen that every time either one of the pins 51 passes between the spear 46 and sleeves 48 the projection 44 on one side will pass above the spear and engage lever 54. This moves the parts to the dotted line position in Fig. 3, and lifts the pawl 56 so that the take-up motion will be inoperative during the time when the loom is missing picks. This part of the device, therefore, is operated from the shed the same as is the miss-pick controlling mechanism described above.

It will be understood, of course, that in this class of looms every time a short weft is brought down into operative position a pick is necessarily missed, because it does not come into contact with the feed rolls. Now if the above described mechanism operated by itself without any further control of the machine the short weft causing the trouble would remain in the hopper and again be brought into position so that the operator would still have to pull out the short weft before the machine could operate properly. In order to provide automatic means for taking out the short weft, the following mechanism is provided, preferably in conjunction with that described above, reference being had to Figs. 12, 13, 14 and 15. In this case the lathe is shown as provided, as usual, with a hopper 69 for holding the weft strand and with operating means therefor. It will be understood, of course, that after a strand reaches the bottom of the hopper it is normally fed into the shed while the lathe beats back. Now if a short weft is in position as indicated in Fig. 12, so that it does not engage the feed rolls, the pick will be missed and the mechanism above described will operate, and while it is operating the lathe will beat forward with the weft strand in position in the hopper. As it comes forward the weft strand passes over a stationary jaw 70 which is mounted on a fixed rod 71 on the frame. At the same time a movable jaw 72 is raised by a cam 74 so as to leave a space between the two jaws into which the end of the short weft strand enters. As the lathe continues to move forward and the cam turns, the jaw 72 is brought down preferably by a spring 73 so as to grip the short strand, and by the continued motion of the lathe this strand is pulled out so that the operator can take hold of it and remove it from the loom without taking any particular pains to select the proper strand. In this way by the

coöperation of the short weft removing arrangement the loom does not have to be stopped and thus a very large percentage of time is saved and a great increase in production secured as has been demonstrated in practice.

While I have illustrated and described a preferred embodiment of the invention, I am aware that many modifications can be made therein by any person skilled in the art and that some parts of the invention can be applied to other types of looms without departing from the scope of the invention as expressed in the claims. Therefore I do not wish to be limited to all the features of construction shown and described, but

What I do claim is:—

1. In a loom for weaving short weft fabrics, the combination with means for forming a shed and means for inserting the weft, of means whereby when a pick is missed from one side, the weft introducing means will be prevented from inserting a weft strand from the other side so that the next pick on the other side will be missed also.

2. In a loom for weaving short weft fabrics, the combination with means for inserting weft strands in the shed alternately from the opposite sides, of means whereby when a pick is missed on either side, the weft introducing means will be prevented from inserting a weft strand from the other side so that the next weft strand will be introduced from the same side.

3. In a loom for weaving short weft fabrics, the combination with means for forming a shed, of means operated by the shed for causing the loom to miss the next succeeding pick, whenever a pick is missed on either side.

4. In a loom, the combination of a lathe, means for forming a shed, means for introducing weft strands alternately from opposite sides, a shaft extending across the loom, a bar connected with said shaft and adapted to engage the under side of the warp threads, and means connected with said shaft and controlled by the position in which the bar is placed by the warp threads for preventing the introducing means from operating on one side immediately after a pick has been missed on the other.

5. In a loom, the combination of a lathe, an oscillatory shaft extending therealong, a bar fixed to the shaft and adapted to engage the shed and to be moved thereby to oscillate the shaft, means for inserting weft strands alternately from opposite sides of the loom, means on each end of the shaft acting when the weft-introducing means fails to operate to introduce a weft on one side, to render the weft-introducing means on the other side inoperative, whereby two weft strands are prevented from being introduced into the shed

in succession from the same side, and means on each end of the shaft whereby when a pick is missed on one side the next pick on the other side will also be missed so as to prevent two weft strands from being introduced into the shed in succession from the same side.

6. In a loom, the combination of a lathe, an oscillatory shaft extending therealong, a bar fixed to the shaft and adapted to engage the under side of the shed and to be raised and lowered thereby to oscillate the shaft, means for inserting weft strands alternately from opposite sides of the loom, means on each end of the shaft acting when the weft-introducing means fails to operate to introduce a weft on one side, to render the weft-introducing means on the other side inoperative, whereby two weft strands are prevented from being introduced into the shed in succession from the same side, and means on each end of the shaft whereby when a pick is missed on one side the next pick on the other side will also be missed, said means comprising a lever operated by said shaft, and means connected with said lever for preventing the feeding of a weft strand in certain positions thereof.

7. In a loom, the combination of a lathe, an oscillatory shaft extending along the same, a bar connected with said shaft, resilient means connected with the shaft for normally holding the shaft in such position as to keep the bar in contact with the shed, an arm near each end of the shaft, a lever on each of said arms, a second lever near each end of the lathe pivoted independently of said shaft and adapted to be engaged by the first lever and held yieldingly in a certain position thereby, a bodily movable feed roll on each end of the lathe for feeding wefts into the shed, and means connected with the last named lever for moving the said feed roll out of operative position.

8. In a loom, the combination of a lathe, a bar extending along the lathe under the shed, resilient means for normally keeping the bar in engagement with the underside of the shed, a lever operated by said bar, a second lever pivotally mounted on the lathe and adapted to be operated by the first named lever in accordance with the position of said bar, said second lever having a projection thereon, and a bodily movable feed roll having a lug thereon in position to be engaged by said projection when the second lever is in a certain position, whereby said feed roll will be held back out of operating position.

9. In a loom, the combination of two sets of feed rolls, one on each side adapted to introduce wefts into the shed, and means whereby when either set of feed rolls fails to introduce a weft into the shed the other

- set of feed rolls will be rendered inoperative until the first named feed rolls introduce a weft into the shed.
10. In a loom, the combination of a weft feeding device on each side adapted to operate alternately, and means operated by the shed whereby when one of the feeding devices fails to operate the other feeding device will be rendered inoperative until the 10 first named feeding device operates to insert a weft in the shed.
11. In a loom, the combination of a feeding device on one side of the loom for weft strands, means operated by the shed for rendering said feeding device inoperative, and means on the other side of the loom for controlling said second means to render it operative again after the loom has missed an even number of picks.
- 20 12. In a loom, the combination of a feeding device for weft strands on one side of the loom, means operated by the shed for rendering said feeding means inoperative, and means on the other side of the loom for 25 restoring said means to operative condition.
13. In a loom, the combination of the lathe, with a lever pivotally mounted thereon, means for inserting wefts alternately from either side, means operated by the shed 30 for moving said lever to a certain position when a pick is missed, and means controlled by said lever for rendering inoperative the weft introducing means on the side opposite that on which the pick was missed after the 35 lever has moved to said position.
14. In a loom, the combination of the lathe, and breast-beam, with a lever pivotally mounted thereon, means for inserting wefts alternately from either side, means for 40 moving said lever to a certain position when a pick is missed, and means controlled by said lever for rendering inoperative the weft introducing means on the side opposite that on which the pick was missed after it has 45 moved to said position, said means comprising a rod mounted on the breast-beam, a sleeve slidable on said rod, and means on the lever for engaging said sleeve when in such 50 position as to prevent the lever from passing over the rod until the lever is moved out of that position.
15. In a loom, the combination of a bodily movable feed roll having a lug movable therewith, a lever pivotally mounted on the 55 lathe and having a projection for engaging said lug for holding the roll in an inoperative position, and means operated by the shed for moving said lever to a position to engage and hold said lug when a pick from 60 the other side of the loom is missed.
16. In a loom, the combination of a bodily movable feed roll having a lug movable therewith, a lever having a projection for engaging said lug for holding the roll in an 65 inoperative position, means operated by the
- shed for moving said lever to a position to engage and hold said lug when a pick from the other side of the loom is missed, and means for then turning the lever to disengage it from the lug so as to permit the feed 70 roll to operate.
17. In a loom, the combination of a bodily movable feed roll having a lug movable therewith, a lever engaging said lug for holding the roll in an inoperative position, 75 means for moving said lever to a position to engage and hold said lug when a pick from the other side of the loom is missed, means for then turning the lever to disengage it from the lug so as to permit the feed roll to 80 operate, an intermittently acting take-up device, and means whereby when said lever is in engagement with said lug the take-up device will be caused to miss two motions.
18. In a loom, the combination of the 85 lathe, with a lever, means for inserting wefts alternately from either side, means for moving said lever to a certain position when a pick is missed, means controlled by said lever rendering inoperative the weft introducing 90 means on the side opposite that on which the pick was missed after it has moved to said position, an intermittently acting take-up device, and means controlled by said lever for preventing the operation of the take-up 95 device while the lever is in said position.
19. In a loom, the combination of the lathe and breast-beam, with a lever pivotally mounted thereon, means for inserting wefts alternately from either side, means operated 100 by the shed for moving said lever to a certain position when a pick is missed, means controlled by said lever rendering inoperative the weft introducing means on the side opposite that on which the pick was missed after it has moved to said position, said means comprising a rod mounted on the 105 breast-beam, a sleeve slidable on said rod, means on the lever for engaging said sleeve when in such position as to prevent the lever from passing over the rod until the lever is moved out of that position, an intermittently acting take-up device, and means controlled by said lever for preventing the operation of the take-up device while the lever is in said 110 position.
20. In a loom, the combination with the lathe and breast-beam, of means for inserting wefts alternately from either side, a spear fixed in the breast-beam, a rod parallel with the spear and located under it, a sleeve slidable on said rod and having a notch therein, a lever pivotally mounted on the lathe and movable under said rod when a weft strand is introduced into the shed in 115 the regular manner, means whereby said lever is moved so as to engage in said notch, when a pick is missed, means controlled by said lever for rendering inoperative the means for making the next pick from the 120 125 130

other side of the loom while said lever is in said notch, a take-up motion, and means controlled by the shed for preventing the operation of the take-up motion while said lever is 5 connected with said notch.

21. In a loom, the combination with the lathe and breast-beam, of a lever supported by the breast-beam, a take-up motion, means connected with the lever for throwing the 10 take-up motion out of operation when the lever is moved to a certain position, and a lever operated by the shed for engaging the said lever connected with the take-up motion when a pick is missed.

15 22. In a loom, the combination with means for introducing weft strands into the shed, means for rendering said weft-introducing means inoperative to introduce a second weft strand into the shed from the 20 other side after a pick has been missed, a take-up motion, and means for rendering the take-up motion inoperative while said weft-introducing means is inoperative.

23. In a loom for weaving short weft fabrics, the combination of means operated by 25 the shed for causing the loom to miss a pick, a take-up motion, and means controlled by the first named means for preventing the operation of the take-up motion when a pick 30 is missed.

24. In a loom for weaving short weft fabrics, the combination of a take-up motion, means for causing the take-up motion to be rendered inoperative whenever a pick is 35 missed, and means whereby when the missing of the pick is caused by a short weft said short weft will be removed automatically as the lathe beats forward.

25. In a loom for weaving short weft fabrics, the combination with means for selecting 40 weft strands and locating them in position to be fed, and means for inserting weft strands in the shed alternately from the opposite sides, of means whereby if a miss-pick 45 is caused by a short weft, said short weft will be removed automatically as the lathe beats.

26. In a loom for weaving short weft fabrics, the combination with means for selecting 50 weft strands and locating them in position to be fed, a hopper for receiving the

weft strands, and means for introducing said weft strands into the shed, of means for rendering the introducing means inoperative to introduce a strand from the side opposite 55 that on which a pick has been missed, and means whereby short weft strands located in position for feeding in the hopper will be automatically removed from the hopper as the lathe beats.

60 27. In a loom for weaving short weft fabrics, the combination of means for selecting weft strands and locating them in position to be fed, a hopper for receiving the weft strands, and means whereby a short weft strand which is not fed into the shed when the lathe is in position for feeding it will be automatically removed from the hopper.

28. In a loom for weaving short weft fabrics, the combination of means for selecting 70 weft strands and locating them in position to be fed, a hopper for receiving the weft strands, and means whereby a short weft strand, which is not fed into the shed when the lathe is in position for feeding it will 75 be automatically removed from the hopper as it beats forward, said means comprising a pair of jaws located adjacent to the end of the lathe and in position to engage the bottom weft strand thereof, and means for 80 opening and closing said jaws as the lathe passes them on its forward stroke.

29. In a loom for weaving short weft fabrics, the combination of a hopper for receiving and feeding the weft strands, means 85 in the hopper for selecting a strand and locating it in position to be fed during the beat of the lathe, a fixed jaw mounted on the frame of the loom, a movable jaw mounted adjacent to the fixed jaw, and 90 means connected with the loom for moving the movable jaw toward the stationary jaw to grip a short weft left in the hopper as the lathe beats.

In testimony whereof I have hereunto set 95 my hand in the presence of two subscribing witnesses.

HENRY E. RATHBUN.
